CLAIM

The ornamental design for a wearable electronic device for the ear, substantially as shown and described.

DESCRIPTION

FIG. 1 is an isometric view of a wearable electronic device for the ear, showing the top, right side and rear of one embodiment of my new design for the left ear.

FIG. 2 is an isometric view thereof showing the top, left side and front of the design.

FIG. 3 is a left side elevational view thereof.

FIG. 4 is a right side elevational view thereof.

FIG. 5 is a front elevational view thereof.

FIG. 6 is a rear elevational view thereof.

FIG. 7 is a top plan view thereof; and,

FIG. 8 is a bottom plan view thereof.

Another embodiment for the right ear is provided, which is a mirror image of the embodiment for the left ear shown in FIGS. 1 through 8.

Stippling and tangency lines in the drawings illustrate the three-dimensional contours of the design and are not intended to indicate surface decorations. The broken lines in the drawings depict portions of the wearable electronic device for the ear that form no part of the claimed design.

1 Claim, 3 Drawing Sheets
